CLAIM

The ornamental design for a tire, as shown and described.

DESCRIPTION

FIG. 1 is a perspective view of a tire showing my new design, it being understood that the tread pattern is repeated throughout the circumference thereof as shown schematically by solid lines, the opposite side being substantially the same as that shown;
 FIG. 2 is an enlarged fragmentary developed plan view of the tire of FIG. 1; and,
 FIG. 3 is an enlarged cross-sectional view of the tire of FIG. 1 taken along line 3—3 in FIG. 2.
